UNITED STATES PATENT OFFICE.

DANIEL H. LAWTON, OF CHICAGO, ILLINOIS.

ARCH-SUPPORT.

1,192,214.

Specification of Letters Patent. Patented July 25, 1916.

Application filed July 17, 1915. Serial No. 40,410.

To all whom it may concern:

Be it known that I, DANIEL H. LAWTON, a citizen of the United States, and a resident of the city of Chicago, county of Cook, and State of Illinois, have invented certain new and useful Improvements in Arch-Supports, of which the following is a specification.

My invention relates to improvements in arch supports for shoes and has for its object the provision of an improved construction of this character which may be readily adjusted to different foot arches and which is simple and efficient in use.

The invention consists in the combinations and arrangements of parts hereinafter described and claimed.

The invention will be best understood by reference to the accompanying drawing, forming a part of this specification, and in which—

Figure 1 is a bottom plan view of arch support embodying my invention, Fig. 2, a side elevation thereof with the cover plate removed, Fig. 3, an enlarged section taken on line 3—3 of Fig. 1, and Fig. 4, a bottom plan view of a modified form of construction.

The preferred form of construction as illustrated in Figs. 1, 2 and 3 comprises an upwardly bowed arch plate 5 and a supplemental reinforcing plate 6 arranged thereunder. Adjacent its front end plate 5 is provided with a depending transversely headed stud 7 and the plate 6 is provided with a plurality of longitudinally elongated slots 8 located at different longitudinal positions in plate 6 and adapted to pass over headed studs 7 when plate 6 is swung to a position substantially at right angles to that indicated in Fig. 1. This arrangement effects a detachably adjustable pivotal connection between the two plates which permits of the ready removal of plate 6 so that the arch in plate 5 may be adjusted. Adjacent its rear end plate 5 is provided with depending longitudinally headed studs 9 and 10 and plate 6 is provided with a corresponding key hole slot 11 adapted to pass over and engage stud 9 and a notch 12 at one edge adapted to engage stud 10. The arrangement is such that plate 7 may be swung readily until the large portion of slot 11 registers with head 9 when said slot may be passed over said stud and a slight movement will securely engage the small portion of

slot 11 under the head of stud 9 and notch 12 under the head of stud 10. To further secure the detachable connection thus effected, I also provide a bead 13 which is struck from the body 5 in position to engage against the corresponding edge of plate 6 when such engagement is effected with said studs. To remove plate 6 all that is necessary is to move the same slightly laterally against the resistance of bead 13 to bring the enlarged portion of slot 11 in registration with slot 9 when plate 6 may be flexed sufficiently to pass over said stud and entirely removed as explained above. When plate 5 is bent to different curvatures of arch the longitudinal distances between studs 7 and the studs 9 and 10 are necessarily varied, so that by locating the slots 8 at different longitudinal positions in slot 11 provision is made for these varying positions and thus provision is made for varying the curvature of the arch in each plate 5 when desired. The top plate 5 is covered with the usual leather cover plate to protect the foot from injury or irritation from contact therewith. The construction disclosed is a simple and efficient one for the purpose and will afford sufficient resiliency to render the use thereof comfortable.

In the modified form of construction illustrated in Fig. 4 the stud 7 and slots 8 have been omitted, otherwise the construction being identical with that previously described. This modified form of construction furnishes a simpler and more economical construction which is suitable for some purposes but is not considered quite as effective although it may be manufactured at less cost.

While I have illustrated and described the preferred forms of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. An arch support comprising an upwardly bowed arch plate; a supplemental plate arranged thereunder; headed studs on the under side of said bowed plate, there be-

- ing a key hole slot in the body of said supplemental plate and a notch in one edge thereof of both engaging said studs; and a yielding stop member on said bowed plate engaging an edge of said supplemental plate to yieldingly hold said slot and notch in engagement with said studs, substantially as described.
2. An arch support comprising an upwardly bowed arch plate; a supplemental plate arranged thereunder; headed studs on the under side of said bowed plate, there being a key hole slot in the body of said supplemental plate and a notch in one edge thereof both engaging said studs; and a yielding stop bead on said bowed plate engaging an edge of said supplemental plate to yieldingly hold said slot and notch in engagement with said studs, substantially as described.
- 10 3. An arch support comprising an upwardly bowed arch plate; a supplemental plate arranged thereunder; laterally shiftable fastenings between said plates; and a stop member on said bowed plate engaging said supplemental plate to yieldingly hold said fastenings together, substantially as described.
- 15 4. An arch support comprising an upwardly bowed arch plate; a supplemental plate arranged thereunder; laterally shiftable fastenings between said plate, and a stop bead on said bowed plate engaging said supplemental plate to yieldingly hold said fastenings together, substantially as de-
- 20 30 35 40 45
- scribed.
5. An arch support comprising an upwardly bowed arch plate; a supplemental plate arranged thereunder; headed studs on the under side of said bowed plate adjacent one end thereof, there being a key hole slot in the body of said supplemental plate and a notch in one edge thereof both engaging said studs; and a headed stud on the under side of said bowed plate adjacent the other end thereof, there being a plurality of longitudinally elongated slots in the corresponding end of said supplemental plate located at different longitudinal positions and adapted to engage said last mentioned stud; and a yielding stop member on said bowed plate engaging an edge of said supplemental plate to yieldingly hold said slot and notch in engagement with said studs, substantially as described.

and adapted to engage said last mentioned stud, substantially as described. 50

6. An arch support comprising an upwardly bowed arch plate; a supplemental plate arranged thereunder; headed studs on the under side of said bowed plate adjacent one end thereof, there being a key hole slot 55 in the body of said supplemental plate and a notch in one edge thereof both engaging said studs; a headed stud on the under side of said bowed plate adjacent the other end thereof, there being a plurality of longitudinally elongated slots in the corresponding end of said supplemental plate located at different longitudinal positions and adapted to engage said last mentioned stud; and a yielding stop member on said bowed plate 60 engaging an edge of said supplemental plate to yieldingly hold said slot and notch in engagement with said studs, substantially as described. 65

7. An arch support comprising an upwardly bowed arch plate; a supplemental plate arranged thereunder; headed studs on the under side of said bowed plate adjacent one end thereof, there being a key hole slot 70 in the body of said supplemental plate and a notch in one edge thereof both engaging said studs; a headed stud on the under side of said bowed plate adjacent the other end thereof, there being a plurality of longitudinally elongated slots in the corresponding 75 end of said supplemental plate located at different longitudinal positions and adapted to engage said last mentioned stud; and a stop bead on said bowed plate engaging an edge of said supplemental plate to yieldingly hold said slot and notch in engagement with said studs, substantially as de-

scribed. 80

In testimony whereof I have signed my name to this specification in the presence 90 of two subscribing witnesses.

DANIEL H. LAWTON.
